LAMP SOCKET

Rob Roy Glass, Rome City, Ind., assignor to
Lyall Electric, Inc., Albion, Ind.

Filed Oct. 22, 1975, Ser. No. 624,944

Term of patent 14 years

Int. Cl. D26—99
U.S. Cl. D26—1 G

FIG. 1

FIG. 2

FIG. 3

FIG. 4

FIG. 5

FIG. 6

FIG. 7

FIG. 8

FIG. 10

FIG. 12

FIG. 11

FIG. 1 is an end view of a lamp socket showing my new design;

FIG. 2 is a side view thereof;

FIG. 3 is an end view of the end opposite that illustrated in FIG. 1 as seen from the right of FIG. 2;

FIG. 4 is a side view thereof of the side opposite that of FIG. 2;

FIG. 5 is a top view thereof;

FIG. 6 is a bottom view thereof;

FIG. 7 is a respective view thereof showing the top, end of FIG. 1, and side of FIG. 2;

FIG. 8 is a perspective view of a lamp socket similar to FIG. 7 but showing a modification of my new design with the top, front end, and right side thereof visible;

FIG. 9 is a rear end view of my modified design;

FIG. 10 is a front end view of my modified design;

FIG. 11 is a perspective view of my modified design with the bottom, rear end, and right side thereof visible; and

FIG. 12 is a left side view of my modified design. I claim:

The ornamental design for a lamp socket, substantially as shown and described.
